UNITED STATES PATENT OFFICE.

ALEXANDER H. KEYS, OF SAN FRANCISCO, CALIFORNIA.

SHOE-EXPANDING APPLIANCE.

Application filed March 22, 1922. Serial No. 545,735.

To all whom it may concern:

Be it known that I, ALEXANDER H. KEYS, a citizen of the United States, and resident of San Francisco, county of San Francisco, 5 and State of California, have invented a new and useful Improvement in Shoe-Expanding Appliance, of which the following is a specification.

My invention relates to an appliance for 10 use by individuals for expanding shoes so that the same may be made to more comfortably fit the feet, particularly in cases where a person is troubled with corns or bunions. Another characteristic of my in- 15 vention resides in an appliance which may perform the function of a shoe tree for main- taining the shape of a shoe when the same is not in use.

The invention possesses other features 20 which will clearly appear as the description now proceeds with reference to the practical embodiment of the invention as illustrated in the accompanying drawing, in which Figure 1 is a longitudinal section of the ap- 25 pliance. Figure 2 is a view in side elevation of the appliance, Figure 3 is a horizontal section of the appliance, Figure 4 is a detail view of an accessory used in connection with the appliance and Figure 5 is a detail per- 30 spective view of still another accessory for use in connection with the appliance.

Referring now to the drawing in detail, I 35 propose to construct the appliance with an irregular shaped frame (1) made preferably from a metal band and shaped as best shown in Figure 3, so as to conform substantially to the inside of a shoe.

Riveted or otherwise fixed as at (2) to the 40 back of the frame (1) is a handle (3) made as a convenient means of inserting the appliance in the shoe and withdrawing the same therefrom. Pivotaly fixed to a trans- 45 verse rod (4) which is fastened to opposite sides of the frame (1) is a lever (5), the same having a fulcrum point on the rod (4) at its pivotal connection therewith, so that the rod may be rocked back and forth relative to the frame. The lower part of the rod (5) is made in the form of a U with 50 its pivotal connection with the rod (4) made substantially in the middle of the U so that the end (6) may terminate in an upwardly presented end and leaving a handle (7) at the opposite end projecting above the frame 55 to be engaged by the hand of the individual

for manipulating the lever. The end (6) is threaded and made to receive a threaded cap (8) for increasing or decreasing the end (6) by turning the cap up or down on the screw threads.

Ranged on opposite sides of the frame (1) in back of the rod (4) are upstanding bearings (9) each one having a key-hole slot (10) made to receive the shanks (11) of the ex- 60 panding heads (12). Arranged on the shanks (11) of each of the expanding heads is a member (13) which is received in the slotted part of the keyhole slot to prevent the shanks (11) from turning in the bearing, thus maintaining the expanding heads 65 (12) fixed against turning relative to the frame, at the same time leaving them free to be withdrawn at will. The expanding heads (12) may be made in various shapes as best shown in Figure 3, the one on the 70 left of the frame is shorter than the one on the right of the frame. To prevent wob- bling of the lever (5) the rod (4) is made with sleeves (4') on each side of the pivotal connection of the lever which holds the lever 75 in the center of the frame and prevents the same from sliding along the rod. Arranged preferably as an integral part of the lever (5) and projecting forwardly thereof 80 adjacent its pivotal connection on the rod 85 (4) is a wedge shaped block (14), the same moving in an orbit around the pivotal connection of the lever and made to have a wiping connection with the ends of the shanks (11) of the expanding heads (12) so 90 as to force the same outwardly against the sides of the shoe when the lever is pulled 95 down toward the handle (3) so that the leather or material of the shoe may be stretched within a restricted area for reliev- 100 ing pressure on a corn or bunion when the shoe is worn. The expanding heads (12) may be interchanged one with the other or ex- 105 panding heads of different shapes may be used or they may be done away with altogether if their use is not required. Hinged to the front of the frame (1) is a frog (15) the same being curved in cross section and adapted to overlie the frame for a greater part of its length and with the cap (8) made 110 to contact with the underside of a frog so as to raise and lower the same according to the relative position of the lever. The frog is used for expanding or stretching po- sitions and the desired effectiveness of the 110

same may be realized by adjusting the cap (8) which will be desirable in using the appliance with shoes of different sizes.

For stretching or expanding restricted areas of the shoe to relieve tension on a corn the button (16) is used with the pin (17) thereof made to be inserted in any one of a series of holes (18) arranged at intervals practically throughout the surface of the frog or at least along both sides thereof so that the button may be used in combination with any one of the holes according to the particular area of the shoe affected.

In using the appliance the lever (5) is moved to a position as best shown in Figure 2 so that the frog (15) is lowered. It is then inserted into the shoe with the expanding heads (12) attached or detached as desired and also with or without the button (16) and when it has been placed in position in the shoe the lever is pulled back as best shown in Figure 1 in dotted lines, thus raising the frog (15) and imparting an outward thrust to the expanding heads.

The button being carried by the frog performs its function as previously explained.

Since the lever in being pulled back to its extended position will be past dead center at its pivotal point the same will be maintained in this position until it is pushed forward again.

From the above it will be readily seen that I have produced not only a convenient and practical shoe tree but that I have also provided means for expanding or stretching the shoe and arranged means for relieving the tension of the shoe on corns and bunions by the accessory which I use in combination with the appliance. The appliance may be

cheaply produced and since it is made of metal it will wear exceedingly well and prove a most practical appliance for its intended use.

I claim:

1. In an appliance of the class described, a frame, a frog pivotally connected at the front of the frame and adapted to move above the same in a horizontal angular plane and means for moving and holding the frog in an elevated horizontal angular plane relatively of the frame, comprising a lever pivotally connected to the frame having one end contacting with the underside of the frame and means for adjusting the contact of the lever end with the under side of the frog, comprising adjustable means carried by the end of the lever and made to provide a contact between the lever end and the under side of the frog.

2. In an appliance of the class described, a frame, a frog pivotally connected at the front of the frame and adapted to move above the same in a horizontal angular plane and means for moving and holding the frog in an elevated horizontal angular plane relatively of the frame, comprising a lever pivotally connected to the frame having one end contacting with the under side of the frame and means for adjusting the contact of the lever end with the under side of the frog, comprising a cap threaded to the end of the lever and made to provide a contact between the lever end and the under side of the frog and means on the frame actuated by the lever for expanding restricted areas of the shoe substantially as and for the purpose described.

ALEXANDER H. KEYS.
